UNITED STATES PATENT OFFICE.

RUDOLF ERNST WAGNER, OF KARLSTAD, SWEDEN, ASSIGNOR TO AKTIEBOLAGET
KARLSTADS MEKANISKA VERKSTADS, OF KARLSTAD, SWEDEN, A MANUFACTURING COMPANY OF SWEDEN.

STRAINER-CYLINDER FOR WOOD-PULP AND CELLULOSE.

1,385,340.

Specification of Letters Patent. Patented July 19, 1921.

Application filed August 9, 1920. Serial No. 402,376.

To all whom it may concern:

Be it known that I, RUDOLF ERNST WAGNER, a subject of the King of Sweden, residing at Karlstad, in the Kingdom of Sweden, 5 have invented a new and useful Improvement in Strainer-Cylinders for Wood-Pulp and Cellulose, for which I have filed applications in Sweden, March 5, 1919, #1049/19; 10 Finland, June 21, 1920, #397/20; Norway, June 22, 1920, #20,647; Germany, June 24, 1920; Austria, June 24, 1920, and of which the following is a specification.

The present invention relates to an improvement in strainer cylinders or rolls for 15 wood-pulp and cellulose, such as are used in the rotary wire-part of wet-machines, in pulp-vats, thickeners for pulp, water-extractors, and collectors for stuff. The invention relates to the type of such straining 20 cylinders which consist of a rotary cylinder divided into cells or compartments and surrounded by a rotary strainer cloth, and which are arranged in such manner that the supply of the material or pulp onto the 25 strainer cloth takes place at a portion of its upward moving surface over the horizontal plane through the axis of the cylinder.

The invention is principally characterized by this that in the interior of the cylinder 30 within the cells a stationary suction box is provided which box is arranged in such manner that during the rotation of the cylinder those cells over which the pulp is supplied onto the strainer cloth, are at first shut off 35 from the suction box, and only after a filter or straining layer has been formed over these cells by natural straining, said cells are put into communication with the suction box owing to the rotation of the cylinder.

40 The suction chamber is preferably arranged in such manner that the said cells over which the pulp is supplied onto the strainer cloth, are at first completely closed by the wall of the suction box, and are afterward moved 45 during the rotation of the cylinder to an opening of a drain conduit in the wall of the suction box, and finally to an opening of the suction chamber in said suction box.

An embodiment of the invention is illustrated in the accompanying drawings, in 50 which Figure 1 shows an axial section on the line I—I in Fig. 2, and Fig. 2 shows a cross section on the line II—II in Fig. 1.

1 denotes the pulp container in which the

cylinder 2 rotates in such manner that only 55 the upper upward moving fourth part of the cylinder is within the container. The cylinder is divided in well-known manner into cells or compartments 3 which are surrounded by a strainer cloth 4. The interior 60 of the cylinder is occupied by a stationary suction box 5 in which there is a partition 6 dividing the interior of the box into two chambers. The larger chamber 7 is the suction chamber, and has at its top an opening 65 of such extension that the uppermost cells in the upper fourth moving upward and the greater portion of the number of cells in the upper downward moving fourth of the cylinder, approximately to the point on 70 the periphery of the cylinder at which the web of pulp gathered on the strainer cloth around the cylinder is removed from the cylinder in suitable manner for instance by means of a removing roll or by blast air, 75 are in communication with said suction chamber. The smaller chamber 8 is provided at its top with an opening 9, as shown in Fig. 2. The said opening is located in such manner that the cells arrive opposite 80 the same only after they have moved a certain distance upward in the pulp in the pulp container 1. During the first period of movement upward through the pulp the cells are thus closed and separated from the 85 chamber 8 by the wall 10 of said chamber. The shaft 11 of the cylinder is supported by bearing frames 12 which also support the pulp container 1. The suction box 5 is journaled on the shaft 11 and is maintained 90 in position by means of the bolts 13. The cylinder is rotated by means of a worm gearing 14.

When during the rotation of the cylinder the cells enter the lower portion of the pulp 95 container 1, the pulp settles on the strainer cloth 4 over the cells, and the water strains through the strainer cloth into the cells and remains in the cells. In this manner the fibers of the pulp are at first steadily and 100 slowly deposited on the strainer cloth. When the cells have been moved upward opposite the opening 9 of the chamber 8, the water flows from the cells into said chamber, whereby more water filters through the 105 strainer cloth onto which more pulp becomes deposited. In this manner there has now been formed a fiber layer or a filter of fiber

on the strainer cloth, so that when afterward the cells arrive in front of the opening of the suction chamber 7 and are thus subjected to the suction said fiber layer serves 5 as a filter for collecting still more pulp fibers.

The cells thus being separated by the wall 10 from the drain or outlet chamber 8, when entering the pulp container, and there 10 being no outlet from the cells, the straining or filtering through of the water will at first be checked and take place very slowly, and the risk of the fibers being brought along by the water will thus be very small. 15 When a fiber layer has been formed outside the cells these will arrive to the outlet 9, and the water flowing out of the cells renders possible an increased straining of the water through the fiber layer and the 20 strainer cloth. When a sufficiently heavy fiber layer has been formed in this manner, said layer is subjected to suction whereby the pulp fibers will first settle to the desired thickness of the layer on the cylinder 25 and afterward said layer is effectively freed from water by the suction.

By locating the suction box in the interior 30 of the cylinder a simple and compact construction is attained so that the width of the entire machine does not become greater than the length of the cylinder.

The water is drained from the suction 35 chamber 7 through a pipe 15 and the water in the chamber 8 is drained through a tube 16.

I claim:

1. In a strainer cylinder for wood-pulp and cellulose, the combination of a pulp container, a rotary cylinder divided into cells, 40 a strainer cloth surrounding said cells and forming the outer surface of said cylinder, an upward rotating portion of said strainer cloth above the horizontal plane through the axis of said cylinder forming one wall of 45 said pulp container, a stationary suction box located in the interior of said cylinder within said cells and having a suction opening opposite the upper part of said portion of the strainer cloth forming a wall of said 50 container, and a wall opposite the lower part of said portion of the strainer cloth, said wall forming a stationary bottom for the

cells covered by said part, for the purpose that during the rotation of the cylinder the cells moving into the pulp container shall 55 at first be closed and shut off from the suction box and afterward placed into communication with said suction box when a filter layer has been formed on the strainer cloth over said cells by natural straining. 60

2. In a strainer cylinder for wood-pulp and cellulose, the combination of a pulp container, a rotary cylinder divided into cells, a strainer cloth surrounding said cells and forming the outer surface of said cylinder, 65 an upward rotating portion of said strainer cloth above the horizontal plane through the axis of said cylinder forming one wall of said pulp container, a wall opposite the lower part of said portion of the strainer cloth, and a stationary suction box located in the interior 70 of said cylinder within said cells and having a suction opening opposite the upper part 75 of said portion of the strainer cloth.

3. In a strainer cylinder for wood-pulp and cellulose, the combination of a pulp container, a rotary cylinder divided into cells, a strainer cloth surrounding said cells and forming the outer surface of said cylinder, an upward rotating portion of said strainer cloth above the horizontal plane through the 80 axis of said cylinder forming one wall of said pulp container, a stationary suction box located in the interior of said cylinder within said cells, the wall of said suction box forming a stationary bottom for the 85 cells covered by the lower part of said portion of the strainer cloth forming a wall of said container, a partition in said suction box dividing the same into two chambers, one of said chambers having an opening 90 opposite the cells covered by the intermediate part of said portion of the strainer cloth, a drain conduit connected to said chamber, the other chamber having an opening 95 opposite the cells covered by the upper part of said portion of the strainer cloth, and means for producing suction in said 100 second chamber.

RUDOLF ERNST WAGNER.
